Patented May 6, 1919.

UNITED STATES PATENT OFFICE.

JULIUS PORTESI, OF LOS ANGELES, CALIFORNIA.

REFRIGERATOR-DOOR LATCH.

1,302,846.

Specification of Letters Patent.

Patented May 6, 1919.

Application filed June 1, 1918. Serial No. 237,799.

To all whom it may concern:

Be it known that I, JULIUS PORTESI, a citizen of the United States, residing at Los Angeles, in the county of Los Angeles and 5 State of California, have invented certain new and useful Improvements in Refrigerator-Door Latches; and I do declare the following to be a full, clear, and exact description of the invention, such as will enable 10 others skilled in the art to which it appertains to make and use the same.

My invention relates to that class of latches employed principally on the doors of comparatively large refrigerators, such 15 as those used in meat markets and the like. Heretofore, most of these latches have required two operations of the hand in order to release them, that is an upward swing of a latch lever and then a forward pull there- 20 of to open the door. The object of my invention however is to provide a latch which by a single pull on a handle will release the latch member and open the door, it being thus much easier to gain access to the in- 25 terior of the ice box or the like.

With the foregoing object in view, the invention resides in the novel construction and arrangement of parts as hereinafter 30 fully described and claimed, the descriptive matter being supplemented by the accompanying drawing which forms a part of this application and in which:

Figure 1 is a side elevation partly in section of the improved latch in operative position, as applied to a door;

Fig. 2 is a side elevation looking in the opposite direction from Fig. 1 and illustrating the door partly opened;

Fig. 3 is a front elevation of the latch 40 applied; and

Fig. 4 is a perspective view of the locking bar and the release lever fulcrumed thereon.

In the drawing above briefly described, the numeral 1 designates a locking bar 45 adapted to be secured to and to project beyond one edge of a refrigerator door or the like D, said bar being shown as provided with an attaching plate 2 which is secured to the door by means of screws, bolts or 50 other fasteners 3. The projecting end of the locking bar 1 coöperates with an L-shaped latch member 4 which is lowered either by gravity or by a suitable spring 5, said latch member being pivoted at 6 to the 55 front end of a horizontal arm 7 carried by the door frame F, said arm preferably hav-

ing an attaching plate 8 secured to the frame by screws or the like 9. It will be observed that the entire length of one arm of the L-shaped latch member 4 and substantially 60 the full length of the other arm of said member, are bifurcated to straddle the arm 7, the solid portion 10 of said last named arm of the latch member resting normally on said arm 7 to limit the downward swing- 65 ing of the former as will be clear from Fig. 1. This arrangement is preferable, but it will be obvious that in all cases, it is not necessary to bifurcate the latch member.

By the arrangement so far described, it is 70 simply necessary to close the door D, whereupon the locking bar 1 will raise the latch member 4 against the tension of spring 5, this spring then coming into play to depress said latch member to the operative position 75 shown in Fig. 1. For now releasing the latch member when it is necessary to open the door, a bell crank lever 11 is fulcrumed at 12 between the furcations of a bifurcated arm 13 which projects downwardly and for- 80 wardly from the projecting end of the locking bar 1, the upper end of said lever 11 being designed for engagement with the latch member 4, while the other arm of said lever is shaped to form an adequate handle. 85 When this handle is pulled forwardly, the upper end of the lever strikes the latch member 4 and consequently raises the same to released position, whereupon a continued forward pull will open the door. In again 90 closing the door, the handle should be re- leased and the door forced shut by pushing thereon. The upper end of lever 11 is prefer- ably formed with a notch 14 to receive the lower edge of arm 7, thus insuring that 95 the latch member shall be raised sufficiently to entirely release the same.

From the foregoing, taken in connection with the accompanying drawing, it will be obvious that although my invention is of 100 extremely simple and inexpensive nature, it will be highly efficient and in every way de- sirable, particular emphasis being laid upon the fact that only one forward pull on the handle is required to first release the latch 105 and then open the door. Since probably the best results are obtained from the se- veral features shown and described, they are preferably followed, but within the scope 110 of the invention as claimed, numerous minor changes may well be made. Also, it is to be understood that the invention is not re-

stricted to use upon refrigerator doors, but may be employed wherever advisable.

I claim:

1. A door latch comprising a bar and means for securing it to the door with one end projecting beyond the free edge of the latter, a vertically moving latch to abut the outer side of said bar end and prevent opening of the door, means for mounting said latch on the door frame, and a vertically swinging latch releasing bell crank fulcrumed to said projecting end of said bar on an axis parallel with said bar, said bell crank having one of its arms extending forwardly to strike and raise said latch, the other arm of said bell crank depending from the fulcrum to form a handle, whereby a single forward pull on said handle will first release said latch and then open the door.
2. A door latch comprising a bar and means for securing it to the door with one

end projecting beyond the free edge of the latter, a vertically moving latch adapted to abut the outer side of said bar end to prevent opening of the door, means for mounting 25 said latch on the door frame, an arm extending forwardly from said projecting bar end, and a vertically swinging latch releasing bell crank fulcrumed on said arm on an axis parallel with said bar, said bell crank 30 having one of its arms extending forwardly to strike and raise said latch, the other arm of said bell crank depending from the fulcrum to form a handle, whereby a single forward pull on said handle will first release 35 said latch and then open the door.

In testimony whereof I have hereunto set my hand.

JULIUS PORTESI.
